UNITED STATES PATENT OFFICE.

GEORGE ERNEST WIGHTMAN, OF PORTLAND, OREGON.

CARPET AND FLOOR CLEANING TOOL.

1,236,126.

Specification of Letters Patent.

Patented Aug. 7, 1917.

Application filed October 2, 1916. Serial No. 123,235.

To all whom it may concern:

Be it known that I, GEORGE E. WIGHTMAN, a citizen of the United States, and a resident of Portland, in the county of Multnomah and State of Oregon, have invented a new and Improved Carpet and Floor Cleaning Tool, of which the following is a full, clear, and exact description.

My invention has for its object to provide 10 a tool having a brush for scrubbing carpets and floors with a cleansing material, which may be applied thereto, the tool having an extending edge for scraping off said material from the carpet when the cleansing process has been completed. The treatment by 15 the said edge also serves to allay the nap. When a wood, linoleum, tile, cork, marble or other similar floor has been cleaned by the use of the brush and the cleansing material, a drier carried by a bracket on the tool may be moved relatively to the tool to an operative position, and the cleansing material may be removed and the floor may 20 be dried thereby.

25 Another object of the invention is to provide the drier which is carried by the bracket with a member for pushing out of the way most of the cleansing material which is heavy with dirt, the drier having 30 in the rear of the said member a resilient member with its bottom concave which flattens when pressure is applied to the tool, thereby forming a suction which is a drying feature of the tool.

35 Additional objects of the invention will appear in the following specification, in which the preferred form of the invention is described.

40 In the drawings similar reference characters denote similar parts in all the views, in which

Figure 1 is a sectional view on the line 1—1 of Fig. 2;

Fig. 2 is a plan view of the tool;

45 Fig. 3 is a sectional view similar to that shown in Fig. 1, but with the brush disposed upwardly and the bracket disposed rearwardly;

50 Fig. 4 is a sectional view similar to that shown in Fig. 3, but with the bracket moved forwardly and the drier disposed against the floor;

55 Fig. 5 is a fragmentary sectional view illustrating the means for holding the bracket yieldingly in predetermined position; and

Fig. 6 is an enlarged transverse sectional view of the drier.

When cleaning carpets and floors, it is desirable that a cleansing material be employed which is of a soapy nature and of a very heavy consistency when applied. When such a cleansing material is used, the scrubbing of the material works it into a foam, which at a certain point in the cleansing process passes away through the action of the air, and by absorption of the fabric. It is at this point that the cleansing material should be squeezed from the floor or carpet and into piles, and then gathered 65 up into a pan which may be provided for this purpose. It will, therefore, be readily understood that at the period when the scrubbing process is finished and the cleansing material should be removed, it is important that the operator have at hand the necessary tool with which the cleansing material may be squeezed from the floor or carpet.

By referring to the drawings, it will be 80 seen that the tool is provided with an operating portion 10 having brackets 11 and 12 extending from one of its sides; there being a threaded orifice 13 in the bracket 12 in which a screw 14 meshes, the said screw 14 85 being provided for pressing the brush-back 15 against the bracket 11. By this means the brush may be detachably secured to the tool.

The operating portion of the tool extends 90 beyond the bracket 11 to form a scraping edge 16, the said scraping edge 16 being curved in the general direction of the side from which the brackets 11 and 12 extend.

At the other side of the operating portion 95 of the tool there is disposed a bracket 17 which has ears 18 each disposed between a pair of ears 19 which extend from the operating portion of the tool. There are orifices in these ears 18 and 19, so that pins 100 20 may be disposed therein which serve to pivot the bracket 17, as will be well understood. In this bracket 17 there is an opening 21 through which a spring 22 is disposed, this spring 22 being secured at 23 105 to the operating portion of the tool, the spring serving to hold the bracket yieldingly either in the position illustrated in Fig. 1 of the drawings, or in the position illustrated in Fig. 3 of the drawings. A detail of this 110 feature of the invention is shown in Fig. 5 of the drawings.

The bracket 17 serves to carry a drier 24. The drier 24 has a forwardly depending leg 25, the function of which is to push the cleansing material which carries the main body of the dirt, in advance of the main portion of the drier proper 26. The position of the depending leg 25 when pressure is applied relatively to the main portion 26 of the drier, is such that the end 25 just 10 touches the floor when the main or body portion of the drier 26 is pressed down flush at the concave surface 27. In this way the points of the main portion or body 26 of the drier in advance and at the rear of its concave portion 27, are more or less active, with the result that the depending leg 25 at 15 times does not touch the floor, and at no time does the depending leg 25 bear against the floor with any pressure. This body portion 26 has its bottom 27 concave so that when the bracket is disposed forwardly, as shown in Fig. 4 of the drawings, and pressure is applied to the tool, the concave bottom 27 of the body portion 26 of the drier 20 will be flattened and form a suction which will assist in removing moisture from the floor. It will also be understood that when the bottom 27 of the body portion 26 of the drier 24 flattens it will be disposed in close 25 proximity to the depending leg 25, which will serve to maintain the said leg in normal position. The drier 24 is preferably manufactured of rubber or other similar material, and to assist in retaining the drier in the bracket I prefer to reinforce the top of the drier 24 with a wire screen 28.

When a carpet is to be cleaned, a cleansing fluid is applied to the carpet, and the carpet is scrubbed with the brush, after 40 which the bracket 17 is moved rearwardly on the operating portion of the tool, and the tool is disposed with the brush extending upwardly. The scraping edge applied to the carpet being then curved so that it may 45 thoroughly scrape the cleansing fluid from the carpet.

When a smooth floor has been cleaned by scrubbing it with the brush, and with the

aid of a cleansing material, the bracket 17 is moved forwardly to the position indicated in Figs. 1 and 4 of the drawings, and the tool is operated so that the depending leg 25 will push the bulk of the cleansing fluid with the dirt from the floor, while the body portion 26 of the drier will serve to 55 dry the floor.

Having thus described my invention, I claim as new and desire to secure by Letters Patent:

1. A drier having a depending leg for removing a fluid and in the rear of the depending leg a resilient member having its bottom concave. 60

2. A drier having a depending leg for removing a fluid and in the rear of the depending leg and adjacent thereto a resilient drier member, the resilient drier member having its bottom concave with its rear edge 65 lower than its forward edge.

3. A support, a bracket movably mounted 70 on the support and adapted to be moved forward to rest against the support, a drier carried by the bracket, and resilient means secured to the support for holding the bracket in any one of a plurality of positions relatively to the support.

4. A support, a bracket movably mounted on the support and adapted to be moved forwardly to rest against the support, a drier carried by the bracket and having a depending leg for removing a fluid and in the rear 80 of the depending leg a resilient drier member having its bottom concave, and resilient means secured to the support for holding the bracket in any one of a plurality of positions relatively to the support. 85

5. A support, a bracket movably mounted on the support and adapted to be moved forward to rest against the support, a drier carried by the bracket, there being an opening in the bracket, and a spring secured to the support and disposed through the opening and against the bracket for holding the bracket in adjusted position. 90

GEORGE ERNEST WIGHTMAN.
